(57) **CLAIM**

We claim the ornamental design for dispenser for roll of bags, as shown and described.

DESCRIPTION

FIG. 1 is a perspective view of a first embodiment of our ornamental design of the dispenser for roll of bags; FIG. 2 is a front view of the dispenser for roll of bags of FIG. 1;

FIG. 3 is a right side view of the dispenser for roll of bags of FIG. 1;

FIG. 4 is a left side view of the dispenser for roll of bags of FIG. 1;

FIG. 5 is a top plan view of the dispenser for roll of bags of FIG. 1;

FIG. 6 is a bottom plan view of the dispenser for roll of bags of FIG. 1;

FIG. 7 is a rear view of the dispenser for roll of bags of FIG. 1; and,

FIG. 8 is a perspective view of the dispenser for roll of bags of FIG. 1.

The broken lines FIG. 8 is for the purpose of illustrating environmental structure and form no part of the claimed design.

1 Claim, 7 Drawing Sheets
